UNITED STATES PATENT OFFICE.

CHARLES F. FREDE, OF ST. LOUIS, MISSOURI, ASSIGNOR TO CAST STEEL PLATFORM COMPANY,
OF ST. LOUIS, MISSOURI, A CORPORATION OF DELAWARE.

CAR-UNDERFRAME.

No. 895,739.

Specification of Letters Patent.

Patented Aug. 11, 1908.

Application filed January 4, 1908. Serial No. 409,325.

To all whom it may concern:

Be it known that I, CHARLES F. FREDE, a citizen of the United States, residing at St. Louis, in the State of Missouri, have invented 5 a new and useful Improvement in Car-Underframes, of which the following is a specification.

My invention relates particularly to the end-sill of a metallic car underframe as applied to that class of car known as "blind-end", or without platforms, and has for its object to provide a strong, rigid, and durable end-sill, having the buffering sill or member integral therewith, and specially designed 15 to resist abnormal shock and to transmit the stress thereon uniformly through the longitudinal sills of the underframe.

It consists in features of novelty as hereinafter described and claimed, reference being 20 had to the accompanying drawing forming part of this specification, whereon,

Figure 1, is a top plan view of my improved end-sill; Fig. 2, a front elevation thereof, and Figs. 3, 4, and 5, vertical transverse sections 25 through the sill on lines 3, 3, 4, 4, and 5, 5, respectively, in Fig. 1.

Like letters and numerals of reference denote like parts in all the figures.

a represents my improved end-sill which is 30 preferably, composed of cast steel integral throughout, and consists mainly, of a front portion *b* (representing the ordinary buffering sill), which is preferably, box-shaped in cross section closed at each end, and having a middle forward extension 1 of reduced depth; 35 and a rear portion *b'* (representing the end-sill proper) which is preferably of an inverted L-shape in cross section formed by the rear wall 2 of the front portion *b* and the rear- 40 wardly extended portion 3 of the top wall of front portion *b*, combined with reinforcing upright transverse ribs 3', which unite the walls 2 and 3 together at suitable intervals along the same.

45 To the outside of each closed end of the rear portion *b'*, which preferably extends beyond and curves rearward from the rear wall 2 of the front portion *b*, is fixed laterally the end portion of the corresponding side 50 longitudinal sill or member 4 (indicated by dotted lines) of the underframe, and from the middle of the rear portion *b'* projects rearwardly a pocket *c* which is adapted to contain the buffering spring 5, with the following 6 and 7 having the intermediate spring

plates 8, and operated by the buffering stem 9 (all as indicated by dotted lines) which is adapted to play horizontally through the openings 10 therefor through the end-sill *a*, and coupled in front to the chafing-plate 11, 60 which co-operates with the buffering stem 12 and springs 13 at each side of the middle buffering stem 9 in the usual well-known manner, the buffering stem 12 passing through openings 14 therefor in the end-sill *a*, and the 65 springs 13 having their housing 15 formed in the rear portion *b'* as shown, or in any other convenient manner.

To the upright side walls 16 of the pocket *c*, which preferably unite with the walls of 70 and extend below the front and rear portions *b* and *b'*, are fixed laterally the end portions of the middle longitudinal sills or members 17 of the underframe, and on the side and middle longitudinal sills or members 4 and 75 17 are fixed the floor-plates of the car frame, the end plate 18 at, and adjacent to its outer edge, overlying the top wall 3 of the rear portion *b'* of the end-sill *a*, and secured thereto by rivets (not shown) which pass through 80 the holes 19 therefor in the top wall 3.

Projecting from the top of the rear portion *b'* for its entire length, or thereabout, adjacent to the holes 19, is an upright web or flange 20 to which is fixed the upright end 85 members (not shown) of the car-body, and which strengthens the rear portion *b'* of the end-sill *a* thereat, the flange 20 also forming an abutment to the said edge of the floor-plate 18.

From the rear wall 2 of the front portion *b* depends an L-shaped bracket *d* which is integral with, and preferably extends laterally beyond the side walls 16 of the pocket *c*, the bracket *d* having two opposite bottom lugs 95 21 between which, to the underside of the bracket *d*, is fixed the carry-iron 22 (indicated by dotted lines broken away) for the coupler-shank.

Through the top wall of the front portion 100 *b*, at, and adjacent to the rear wall 2, on each side of the longitudinal center of the underframe, is an opening 23 for receiving the end portion of an upright bar 24 (indicated by dotted lines) forming a member of the vestibule diaphragm frame and which in the present case is T-shaped in cross section, but may be otherwise shaped as found most suitable, and butts at its lower end on the bottom of the front portion *b* as shown. Each 110

- bar 24 is secured laterally to a flange 25 which projects upward from the top of the front portion *b* and is integral therewith, the bar 24 being combined preferably, with two auxiliary upright bars 26 fixed laterally to an intermediate lug or flange 27 projecting upward from the top of the rear portion *b'* immediately behind the opening 23, the bars 26 butting at their lower ends on the top of the rear portion *b'* and at their front edges against the bar 24, whereby a strong and rigid attachment of the bars 24 and 26, or equivalent members to the end-sill *a* and a corresponding resistance of the vestibule diaphragm frame to undue stress are insured. From the bottom of the front portion *b* project lugs 28 to which are coupled the clevises 29 for the safety anchor chains (not shown).
- 26 In the above construction, by making the front portion or buffing still *b* integral with the rear portion or end-sill proper, combined with the middle extension 1 of the front portion *b*, greatly increased strength and rigidity of the end-sill *a* for resisting transverse stress is obtained. Moreover, by forming the rear portion *b'* along its top wall 3 with an upwardly projecting web or flange 20 the strength of the end-sill *a* to resist upward and downward stress is increased, and this feature combined with the rigid attachment of the side and middle longitudinal sills 4 and 17 respectively, to the ends of the sill *a* and the sides of the pocket 35 *c* projecting therefrom, increased rigidity and resistance of the entire underframe to abnormal stress or shock is insured.
- What I claim as my invention and desire to secure by Letters Patent is:
- 40 1. In a car underframe of the class described, a cast metal end-sill integral throughout and comprising a front portion box-shaped in cross section forming the buffing sill and having a front extension of reduced depth, and a rear portion of an inverted L-shape in cross section forming the end-sill proper and adapted to be fixed to the longitudinal sills of the underframe, substantially as described.
- 45 2. In a car underframe of the class described, a cast metal end-sill integral throughout and comprising a front portion box-shaped in cross section forming the buffing sill and having a front extension of reduced depth, and a rear portion of an inverted L-shape in cross section forming the end-sill proper and adapted to be fixed to the longitudinal sills of the underframe, the said front portion having an opening through the top

for the insertion therethrough endwise of an upright member of the vestibule diaphragm frame, and means for the attachment thereto of the said member, substantially as described.

3. In a car underframe of the class described, a cast metal end-sill integral throughout and comprising a front portion box-shaped in cross section forming the buffing sill and having a front extension of reduced depth, a rear portion of an inverted L-shape in cross section forming the end-sill proper and adapted to be fixed to the longitudinal sills of the underframe, and an upright flange on the said rear portion for the attachment thereto of an upright member of the vestibule diaphragm frame, substantially as described.

4. In a car underframe of the class described, a cast metal end-sill integral throughout and comprising a front portion box-shaped in cross section forming the buffing sill and having a front extension of reduced depth, a rear portion of an inverted L-shape in cross section forming the end-sill proper and adapted to be fixed to the longitudinal sills of the underframe, and an upright flange on the said rear portion for its entire length or, thereabout, for the attachment thereto of the upright members of the car body, substantially as described.

5. In a car underframe of the class described, a cast metal end-sill integral throughout and comprising a front portion box-shaped in cross section forming the buffing sill and having a front extension of reduced depth, a rear portion of an inverted L-shape in cross section forming the end-sill proper and adapted to be fixed to the longitudinal sills of the underframe, a pocket projecting rearward from the said rear portion and adapted to contain the springs and followers of the middle buffing-stem, housings in the rear portion for the springs and followers of the side buffing stems, and the said portions having openings therethrough for the play of the said stems, lugs depending from one of the said portions for the safety anchor chains, and a bracket depending from one of the said portions for the attachment thereto of the coupler-shank carry-iron, substantially as described.

In testimony whereof I have signed my name to this specification in the presence of two subscribing witnesses.

CHARLES F. FREDE.
